United States Patent Office.

PHILO B. SHELDON, OF ROCHESTER, NEW YORK.

Design No. 4,463, dated November 8, 1870.

DESIGN FOR A TOASTER AND BROILER.

The Schedule referred to in these Letters Patent and making part of the same.

I, PHILO B. SHELDON, of Rochester, Monroe county, in the State of New York, have invented and produced a new and original Design for Bread-Toaster and Broiler, of which the following is a specification.

My invention consists in a star-shaped design for a bread-toaster and broiler; and I do declare that the following is a full and exact description of the same, reference being had to the accompanying drawing making part of this specification.

Figure 1 in the drawing represents a front view of said toaster, which is made of wire, and provided with a wood handle.

Letter *a* represents the wood handle.

b represents the shank, which enters the handle at ferrule *c*, in two pieces of wire, which are double, each separate half being placed side by side, and so spread in the handle as to represent open jaws or tongs at letter *d*, or star.

Letter *e* represents a ring, which is used as a slide,

to compress the jaws, at letter *d*, or star, for the purpose of holding the article being toasted or broiled.

Letter *f* represents a twist in the wire, which is for the purpose of holding each half in shape.

Figure 2 represents a side view, which shows each separate half of jaws.

The construction of the jaws is such that, when the ring *e* is shoved back to the handle, the jaws spread apart by means of the natural spring of the wire, and are closed again by sliding the ring toward the letter *d*, or star.

I claim as my invention—

The star design and configuration, herein described and represented, for a bread-toaster or meat-broiler.

PHILO B. SHELDON.
